Filed Oct. 3, 1972, Ser. No. 294,537

Term of patent 14 years

Int. Cl. D7—01

U.S. Cl. D7—64

FIG. 1 is a perspective view of a pitcher embodying my new design;

FIG. 2 is a side elevational view thereof;

FIG. 3 is a front elevational view thereof;

FIG. 4 is a rear elevational view thereof;

FIG. 5 is a top plan view thereof;

FIG. 6 is a bottom plan view thereof; and

FIG. 7 is a fragmentary vertical sectional view thereof on an enlarged scale taken through its pouring spout.

A side elevational view taken from the side opposite that shown in FIG. 2 is substantially a mirror image thereof.

I claim:

The ornamental design for a pitcher, as shown and described.
